UNITED STATES PATENT OFFICE.

FREDERICK CHARLES ROSE, OF CHATTANOOGA, TENNESSEE, ASSIGNOR TO GARNET CARTER CO. INC., OF CHATTANOOGA, TENNESSEE.

TRADE-STIMULATING MEANS.

1,312,922.

Specification of Letters Patent.

Patented Aug. 12, 1919.

Application filed March 24, 1919. Serial No. 284,717.

To all whom it may concern:

Be it known that I, FREDERICK C. ROSE, a citizen of the United States, residing at Chattanooga, in the county of Hamilton and State of Tennessee, have invented certain new and useful Improvements in Trade-Stimulating Means, of which the following is a specification.

This invention relates to improved means for use in stimulating trade and increasing the patronage of merchants, tradesmen, etc. The main object of the invention is to provide devices which will enable purchasers to secure premiums in addition to the merchandise bought. A further object is to provide a button or check card and buttons or checks to be secured to the same, so that a new system of securing trade may be employed. A still further object is to provide an improved card of simple and inexpensive construction containing suitable pockets to receive value checks and provided with spaces to receive the printed matter informative of the manner of using the card and of the premiums obtainable through purchasing goods from a designated merchant.

With the foregoing objects outlined and with other objects in view, the invention consists in the novel features hereinafter described in detail, illustrated in the accompanying drawing, and more particularly pointed out in the appended claim.

Referring to the drawing:—

Figure 1 is a front view of the improved card.

Fig. 2 is a rear view of the same.

Fig. 3 is a sectional view of a detail.

Fig. 4 is a perspective view of one of the buttons or checks adapted to be secured to the card.

In the drawing 1 designates a sheet of suitable fibrous material, such as paste board, provided with a plurality of rows of apertures 2. These apertures are preferably of circular shape but they may be of any other suitable configuration. Located below the apertures is a space 3 designed to receive printed instructions as to the use of the card. A backing 4 is secured to the rear side of the sheet and the portions of said backing which cover the apertures are provided with an adhesive substance 5, as shown in Fig. 3.

The rear side of the backing sheet is divided by the lines 6 into a series of spaces 7 to receive printed matter relating to pre-

miums obtainable by the use of the card and instructions used in ordering premiums.

The card is used in connection with buttons or checks 8 having value designations 9 and these buttons or checks are adapted to be moistened and secured to the adhesive 60 provided on the backing 4. The buttons or checks are shaped to conform to the shape of the apertures 2 and it will be understood that if the apertures are of other shape than circular, then the buttons or checks will be 65 of like shape.

The face of the sheet 1 is provided with printed matter 10 arranged adjacent the apertures 2 for the purpose of informing the 70 user regarding the value of the buttons or checks to be placed in the apertures. My idea is to have the top row of apertures receive only five cent checks; the second row ten cent checks; the third row twenty-five 75 cent checks; the fourth row 50 cent checks and the last two rows one dollar checks, but this arrangement may be varied as desired. The card shown in the drawing is designed to receive buttons or checks representing 80 fourteen dollars and a half but the printed matter may be changed to represent various other amounts.

In use, the merchant gives each of his customers one or more of the cards, and when 85 the customer makes a purchase the tradesman gives the purchaser buttons or checks having a value equal or approximately equal to the cost of the goods. The card holder then places these buttons or checks in the 90 apertures designated to receive buttons of this value. For example, it will be assumed that the amount paid for the goods is one dollar and thirty cents, then the merchant will give the purchaser one dollar button 95 and three ten cent buttons. The purchaser places these on his card at the designated places and when the card is filled, he can refer to the first list on the rear side of the card and select the premium given for one 100 full card of buttons, or he may wait until he has two or three full cards and then make a selection in the second or third list. After the holder has made his selection he will place his name and address in the last space 105 on the rear of the sheet and send the card to the premium department of the merchant.

From the foregoing, it will be seen that I have devised a novel means for stimulating or increasing trade and that the construc- 110

tion of my button card will furnish improved facilities for readily educating the public as to the use of the card.

What I claim and desire to secure by Letters Patent is:

A trade stimulating means comprising a substantially rigid card of fibrous material have a series of spaced apertures extending over the greater portion of the same, a delineated space provided on said card and containing printed matter as to the use of the card, a backing sheet attached to and covering the rear side of the card and provided with an adhesive substance forming a bottom coating for said apertures, the card

being provided adjacent each of the apertures with a value mark designating the value of a value check to be inserted in the aperture, and a series of ungummed value checks of a thickness substantially the same as the thickness of the card, provided with value designations corresponding to the value marks on the card, said checks being adapted to be inserted in the apertures and secured to the adhesive substance, and in inserted position having their upper surfaces substantially flush with the upper surface of the card.

FREDERICK CHARLES ROSE.

Copies of this patent may be obtained for five cents each, by addressing the "Commissioner of Patents, Washington, D. C."
